UNITED STATES PATENT OFFICE.

CHARLES ALGERNON PARSONS AND ALFRED QUINTIN CARNEGIE, OF NEWCASTLE-UPON-TYNE, AND STANLEY SMITH COOK, OF WALLSEND, ENGLAND; SAID CARNEGIE AND SAID COOK ASSIGNEES TO SAID PARSONS.

MACHINE-TOOL.

1,234,379.

Specification of Letters Patent. Patented July 24, 1917.

Application filed February 28, 1915. Serial No. 10,103.

To all whom it may concern:

Be it known that we, The Honorable Sir CHARLES ALGERNON PARSONS, K. C. B., of Heaton Works, Newcastle-on-Tyne, in the 5 county of Northumberland, England, ALFRED QUINTIN CARNEGIE, of Heaton Works, Newcastle-on-Tyne, in the county of Northumberland, England, and STANLEY SMITH COOK, of Turbinia Works, Wallsend-on-Tyne, in the county of Northumberland, England, have invented certain new and useful Improvements in and Relating to Machine-Tools, of which the following is a specification.

15 The present invention relates broadly to machine tools such as for example gear cutting and like machines of the type in which, two juxtaposed members are adapted to rotate in contact in the same direction about 20 a common axis, one of the members which acts as an indexing or dividing member being driven from a source of power, while the second member carrying the work is rotated by gearing from the first member and 25 at a different rate therefrom.

The present invention relates more particularly to machines of this class, such as are described in connection with Figures 1 to 3, in the specification of British Letters Patent No. 29,380 of 1912.

It has been found by experiments with gear cutting machines involving the use of superposed members one of which carries the work, that if both members rotate in 35 the same direction and consequently with small relative motion between their contacting surfaces, then on any attempt being made to transmit considerable pressure across those contacting surfaces, irregular 40 jerky motion of the work carrying member results due to the lubrication being imperfect owing to the small relative motion between the surfaces, the friction being probably on the border line between metallic and viscous friction.

45 The object of the present invention is to overcome the above difficulties and to provide an improved construction of tool of the type indicated.

50 The present invention consists in a machine tool of the type indicated in which the secondary member carrying the work is supported by contact with stationary surfaces.

The present invention further consists in

a machine tool of the type indicated in 55 which the secondary member carrying the work is supported by a stationary frame surrounding the first member and the connecting gearing.

The present invention also consists in a 60 gear cutting machine embodying the present invention and comprising a primary member rotating about a vertical axis, a stationary frame surrounding the member, a secondary member co-axial with the first 65 member carried within the frame and adapted to be rotated by gearing from the primary member, but at a different rate therefrom.

The present invention further consists in 70 the improved machine tools hereinafter described.

Fig. 1 is a part cross-sectional elevation showing the present invention applied to a gear cutting machine.

Fig. 2 is a part sectional plan of Fig. 1.

Fig. 3 is a part cross-sectional elevation showing the present invention applied to a modified form of gear cutting machine.

Fig. 4 is a part sectional plan of Fig. 3. 80

In carrying this invention into effect according to one form and as applied to a gear cutting machine (see Figs. 1 and 2) there is provided a horizontal bed *a* preferably of box girder formation and having a suitably bushed vertical bearing, *b*, therein.

The work carrying table *c* hereinafter called the secondary member is provided with a stem *d* to fit the bushed hole in the bed plate, while the primary member takes 90 the form of a ring element *e* constrained to rotate concentric with the axis of the secondary member by a suitable projection or boss *f* upon the bed. The primary member *e* carries the driven member *g* of the parent 95 or indexing gear.

Surrounding the primary member a stationary ring-like member or frame *h* is provided, secured to the upper side of the bed and provided at its upper edge with a suitably surfaced rim *j*. The secondary member is adapted to rotate with its under side in contact with the rim *j* of the frame. 100

The gear train employed between the primary and secondary members to provide 105 the desired shift of phase may conveniently consist of a combined spur wheel *k* and bevel pinion *l* adapted to rotate about a ver-

tical spindle secured to the primary member *e*, the spur wheel *h* engaging a stationary pinion *m* co-axial with the primary member and secured to the above mentioned 5 boss *f* upon the bed.

The bevel pinion *l* meshes with a bevel wheel *n* upon a shaft *o* carrying a worm *p* and supported in bearings *q* upon the primary member *e*, the worm being adapted 10 to engage with and drive a worm wheel *r* secured upon the secondary member.

The effect of this train is that upon the primary member being rotated by the parent gear the spur wheel upon the vertical spindle is rotated and consequently the bevel pinion thus driving the worm *p* engaging the worm wheel *r* upon the secondary member the whole being so arranged that the secondary member *c* rotates in the same direction as but at a rate different from that 20 of the primary member *e*.

Figs. 3 and 4 show the application of the stationary frame *j* to a machine in which the primary and secondary members and 25 the intermediate gearing are similar to the first described form with the difference that instead of the pinion *m* being secured to a stationary boss it is secured to a ring-like member *s* carrying worm wheel teeth *t* and 30 adapted to be driven by a worm *u*.

The effect of this construction is that whereas in the first form with a given train of gear wheels, the rate of movement of the secondary member *c* with respect to the primary member *e* depended upon the rate at which the vertical spindle on the primary member moved around the stationary pinion *m*, in this modification (Figs. 3 and 4) by imparting a backward motion to the ring 35 carrying the pinion *m*, the ratio between the speeds of the secondary and primary members *c* and *e* may be increased.

It will be understood that the driving member of the parent gear, *i. e.*, the worm 45 *v* is carried upon a shaft *w* which may conveniently have bearings *x* in the frame *h*, and which is driven from the same shafting as the tooth forming device *y* for instance, the hob when such is employed. In the last 50 described form the worm *u* which rotates the pinion *m* in the backward direction may also be driven from the same shaft as the driving member *v* of the parent gear.

It will be seen that the constructions indicated provide a very satisfactory arrangement of parts and the use of the frame member *h* allows the gearing to be well protected from chips of metal and dirt, while suitable hand holes allow for access where 60 required.

At Figs. 4 and 5 of the before mentioned Letters Patent, a construction is illustrated in which the difficulty as to low rubbing speed of the secondary table upon its support does not occur as the secondary table 65

is in that construction adapted to bear directly upon the bed of the machine while the primary member in the form of a double toothed ring rotates around the secondary member.

In such a construction however, it is necessary to mount the phase changing gears upon the secondary member and although the position of the point of contact of the final drive shifts in relation to the cutter, 70 it has a constant regular position in relation to the work, a disadvantage which is avoided when the phase changing train is supported on a primary table, as in the constructions hereinbefore described.

Having now described our invention what we claim as new and desire to secure by Letters Patent is:—

1. In a machine tool in combination, a driven indexing member, a work carrying 85 member co-axial with said member, gear means for rotating said work carrying member from the first member at a different rate from the rate of rotation of said driven member, said gear means being carried on 90 said driven member and a stationary surface adapted to support said work carrying member as set forth.

2. In a machine tool in combination, a driven indexing member, a work carrying 95 member, means carried upon said driven member for rotating said work carrying member from the first member at a different rate from the rate of rotation of said driven member and a stationary frame surrounding 100 said driven member and said gearing and having stationary surfaces supporting said work carrying member, as set forth.

3. In a gear cutting machine in combination, a driven indexing member, a work 105 carrying member, gear means upon said driven member for rotating said work carrying member from said driven member at a different rate from the rate of rotation of said driven member and a stationary surface 110 adapted to support said work carrying member, as set forth.

4. In a gear cutting machine in combination, a bed, a bearing in said bed, a primary 115 indexing member adapted to rotate about a vertical axis and concentric with said bearing, a stationary frame surrounding said primary member, a secondary work carrying member co-axial with said primary member, said secondary member being supported by said frame, a stem upon said secondary member engaging said bearing and 120 gearing carried upon said primary member and connecting said primary and secondary members and adapted to drive said secondary member from said primary member at a different rate therefrom, as set forth.

5. In a machine tool in combination, a work table, a bed, a stem upon said table, a bearing in said bed co-acting with said 130

- stem, a worm wheel attached to said table, a ring member constrained to rotate co-axially with said table, indexing teeth upon said ring, driving means engaging said teeth, a circular rack positioned between said table and said ring member and co-axially with said table, a stud upon said ring member, the axis of said stud being parallel to the axis of rotation of said ring member, 5 a member adapted to rotate upon said stud and having teeth engaging said circular rack, bevel teeth upon said member, a spindle, bearings upon said ring member to support said spindle, a bevel wheel upon 10 said spindle in engagement with said bevel teeth, a worm upon said spindle in engagement with said worm wheel and a ring-like frame attached to said bed surrounding said ring member and supporting said table.
- 15 6. In combination in a machine tool, a bed, a work carrying table constrained to rotate about a vertical axis in said bed, a frame secured to said bed and lying between said bed and said table, a bearing surface upon the upper side of said frame, a bearing surface upon the under side of said table co-acting with said last mentioned surface to support said table, said bearing surface being situated near the circumference of 20 said table, an indexing member co-axial with said table and within said frame, driving means for said indexing member, a gear train carried by said indexing member, said train acting to rotate said table from said indexing member and at a different rate 25 therefrom.
- 20 6. In combination in a machine tool, a bed, a work carrying table constrained to rotate about a vertical axis in said bed, a frame secured to said bed and lying between said bed and said table, a bearing surface upon the upper side of said frame, a bearing surface upon the under side of said table co-acting with said last mentioned surface to support said table, an indexing member co-axial with said table and within said 30 frame, driving means for said indexing
- member, a gear train carried by said indexing member, said train acting to rotate said table from said indexing member and at a different rate therefrom.
7. In combination in a machine tool, a bed, a work carrying table constrained to rotate about a vertical axis in said bed, a frame secured to said bed and lying between said bed and said table, a bearing surface upon the upper side of said frame, a bearing surface upon the under side of said table co-acting with said last mentioned surface to support said table, said bearing surface being situated near the circumference of said table, an indexing member co-axial 40 with said table and within said frame, driving means for said indexing member, a gear train carried by said indexing member, said train acting to rotate said table from said indexing member and at a different rate 45 therefrom.
7. In combination in a machine tool, a bed, a work carrying table constrained to rotate about a vertical axis in said bed, a frame secured to said bed and lying between said bed and said table, a bearing surface upon the upper side of said frame, a bearing surface upon the under side of said table co-acting with said last mentioned surface to support said table, said bearing surface being situated near the circumference of said table, an indexing member co-axial 40 with said table and within said frame, driving means for said indexing member, a gear train carried by said indexing member, said train acting to rotate said table from said indexing member and at a different rate 45 therefrom.

In testimony whereof, we affix our signatures in presence of two witnesses.
